F1-2

UNITED STATES PATENT OFFICE.

JOHN A. WIENER, OF ROTHSCHILD, WISCONSIN.

STEAM-FLOW REGULATOR.

Application filed February 4, 1922. Serial No. 534,260.

This invention relates to an improved type of a regulator for a boiler plant whereby a control valve connected with the driving stokers or in a water inlet pipe, or in 5 a fan draft pipe, is adapted to be automatically operated to speed up the stokers or fans or allow more feed water to enter the boilers depending upon the load pull in the steam line and the velocity of steam through 10 an orificed plate within the steam header of the boiler plant.

It is an object of this invention to provide a steam controlled regulator for a boiler plant adapted to automatically operate 15 a valve which can be connected to control driving stokers, the draft to fans, the inlet of boiler feed water, or other functions.

It is also an object of the invention to provide a regulator mechanism adapted to be 20 governed by the load pull in a steam header.

Another object of the invention is to provide a valve control mechanism adapted to be connected with a steam header on opposite sides of an orificed plate disposed transversely within said header to cause automatic operation of a valve depending upon the load pull in the steam header.

It is a further object of this invention to provide a valve regulator wherein a 30 normally balanced mechanism is connected with a control valve to actuate the same when the mechanism is thrown out of balance by the shifting of fluids caused by the velocity of steam through an orificed plate 35 in a steam line.

It is an important object of this invention to provide a regulating device for a boiler plant adapted to be actuated depending upon the load pull in the steam header to 40 cause operation of a control valve which may be connected to steam inlet pipes, to draft fans, to turbines, to driving stokers, to boiler feed water inlet pipes, or to other mechanism to govern the same.

Other and further important objects of 45 this invention will be apparent from the disclosures in the specification and the accompanying drawings.

The invention (in a preferred form) is 50 illustrated in the drawings and hereinafter more fully described.

On the drawings:

Figure 1 is an elevation of the regulator, embodying the principles of this invention,

showing parts broken away and parts in 55 section.

Figure 2 is a top plan view thereof.

Figure 3 is an enlarged detail section taken on the line 3—3 of Figure 1.

Figure 4 is an enlarged fragmentary detail section taken on line 4—4 of Figure 2.

Figure 5 is a fragmentary detail section taken on line 5—5 of Figure 2 with parts of the supporting frame omitted.

As shown on the drawings:

The reference numeral 1 indicates a supporting frame having a pair of oppositely disposed horizontal side angle bars 2 secured thereto. Rigidly secured on the top flanges of the frame side bars 2 are two 70 plates 3 having transverse grooves 4 therein. Resting in the grooves 4 of the frame plates 3 are the knife edge portions 5 of a shaft 6. Secured to the shaft 6 is a balance beam 7. Securely mounted on one end of the balance beam 7 is an upwardly projecting upper cylinder or receptacle 8. Mounted on the opposite end of the balance beam 7 is a downwardly projecting lower cylinder or receptacle 9 which is filled with mercury and is 80 connected with the upper cylinder 8 by means of a small pipe 10 as illustrated in Figure 1. Connected to the balance beam 7 near the cylinder 8 is the lower end of a heavy coiled spring 11, the other end of 85 which is connected to a screw bolt 12 adjustably engaged in a bracket 13 supported on the top of the supporting frame 1. The spring 11 may be tensioned by adjustment 90 of the screw bolt 12 and acts to hold the balance beam 7 in a balanced adjustment.

Secured to the shaft 6 is one end of a yoke 14. The yoke 14 supports a feed screw 15 adapted to be turned by a knurled head 16 to cause a block 17 to travel on the feed screw. Pivottally connected to the adjustable block 17 is the upper end of a connecting rod or link 18, the lower end of which is pivotally connected to a block 19 engaged on a feed screw 20 supported in a lower yoke 21. One end of the yoke 21 is pivotally connected to the supporting frame 1. Pivotally connected to the lower yoke 21 is the upper end of a connecting rod 22 having a turnbuckle 23 connected therein. The connecting rod 22 is connected to a control valve 24 which may be connected in a boiler feed water pipe, in a fan draft

pipe, in the steam supply pipe of a turbine, or connected with the driving stokers of a boiler plant as preferred.

Connected to the top of the upper cylinder 8 is one end of a pipe 25 having a pipe coil 26 connected therein. The other end of the pipe 25 has connected therein an emergency valve 27, a condenser 27^a and a second valve 27^b. A pitot tube 28 is connected to the valve 27. The pitot tube 28 is inserted into a steam line pipe or steam header 29 on the lower pressure side of an orifice plate or baffle member 30 having an orifice 31 therein. Connected to the upper end of the lower cylinder 9 is one end of a pipe 32 having a pipe coil 33 connected therein. The other end of the pipe 32 has connected therein a condenser 34 and emergency valves 34^a which are arranged in a manner similar to the arrangement of the condenser 27^a and the valves 27 and 27^b. A pitot tube 35 is connected with one of the valves 34^a and projects into the steam header 29 on the high pressure side of the orifice plate 30. The direction of flow of steam through the steam header 29 is indicated by arrows as shown in Figures 2 and 3 of the drawings.

The operation is as follows:

Steam flows in the direction of the arrow through the steam header 29 and during its passage contacts the baffle or orifice plate 30 thereby partially obstructing the flow of steam setting up a differential or velocity pressure within the steam header on the high pressure side of the orifice plate causing condensation of some of the steam. The condensed steam is forced through the pitot tube 35, through the valves 34^a and the condenser 34 and then through the pipe 32 and the coil 33 into the top of the mercury cylinder 9. When there is no pressure in the steam header the cylinder 9 is in balance with the cylinder 8. The condensed steam or water which is forced into the cylinder 9 acts to force mercury from the cylinder 9 out through the pipe 10 up into the upper cylinder 8. The cylinder 8 together with the pipes and coils are filled with condensed steam or water. The mercury entering the cylinder 8 thus acts to replace a like volume of water in said cylinder thereby forcing the displaced water through the pipe 25 and coil 26 back into the steam header 29 through the valves 27 and 27^b and the condenser 27^a, then through the pitot tube 28 on the low pressure side of the orifice plate 30. When the pressure in cylinder 9 drives or forces a sufficient quantity of the mercury into the cylinder 8, the increased weight of the cylinder 8 causes the balance beam 7 to tip thereby lowering cylinder 8 and elevating cylinder 9. The shaft 6 is thus rocked on its knife edges 5 thereby swinging the feed screw yoke 14 upwardly. The

lower feed screw yoke 21 is thus swung upwardly whereby the rod or stem 22 is lifted to operate the control valve 24.

With the valve 24 connected in the feed water pipe of a boiler plant the increase in the load pull in the steam header also causes increase in the velocity of the steam through the orifice plate 30, thereby causing operation of the regulator mechanism as hereinbefore described and opening of the control valve 24. Additional water is thus permitted to enter the boiler. As the load pull in the steam header drops off the regulator automatically acts to proportionately close the control valve 24 to regulate the supply of water.

When there is no load pull in the steam header the mercury from the upper cylinder 8 flows back into the lower cylinder 9 thereby causing the balance beam to swing back into a balanced position due to the increased weight of the cylinder 9 and the action of the coiled spring 11.

The pipe coils 26 and 33 are provided to afford sufficient resiliency in the pipe lines to permit the balance beam to be operated. The adjustable screw block mechanisms are provided for the purpose of permitting proper adjustment of the control valve.

The control valve 24 may be positioned to govern turbines, boiler stokers, draft fans, or other mechanisms which may be related to a boiler plant and are to be automatically operated depending upon the consumption of steam or load pull in the boiler steam header.

I am aware that numerous details of construction may be varied through a wide range without departing from the principles of this invention, and I therefore do not purpose limiting the patent granted otherwise than necessitated by the prior art.

I claim as my invention:

1. A regulator of the class described comprising a frame, a shaft, knife edges formed on said shaft, resting on said frame, a balance beam mounted on said shaft, cylinders supported on the ends of said balance beam, a pipe connecting said cylinders, adjustable resilient means connected to said balance beam and to said frame to hold the balance beam in a balanced position, a pipe connecting said cylinders, a second pipe connected to one of said cylinders, a pipe coil connected intermediate the ends of said second pipe, a pitot tube attached to the end of said second pipe, a third pipe connected to the other cylinder, a pipe coil connected in said third pipe, a pitot tube connected to the end of said third pipe, an upper yoke secured to said shaft, a feed screw supported thereon, a block on said feed screw, a lower yoke pivotally supported on said frame, a feed screw therein, a block

on said feed screw, a connecting rod pivoted to said blocks, a control means, and a member connecting the control means with said lower yoke to cause operation of the control means when the regulator is operated.

2. The combination with a boiler steam header and a boiler feed water control valve, of an apertured plate secured in said steam header for the purpose of producing a velocity pressure therein, pitot tubes projecting into the steam header on opposite sides of the apertured plate, a balance mechanism, a lower receptacle secured on said balance mechanism containing mercury, an upper receptacle secured on said balance mechanism containing water, a pipe connecting said receptacles, a second pipe connecting said upper receptacle with the pitot tube on the lower pressure side of

said apertured plate, a third pipe connecting the lower receptacle with the pitot tube on the high pressure side of said apertured plate, and adjustable means connected with the control valve adapted to be operated by the balance mechanism to cause regulation of the control valve as the load pull increases in the steam header and causes a tipping of the balance mechanism due to condensed steam from the high pressure side of the steam header flowing into the lower receptacle to force mercury therefrom into the upper receptacle and water from the upper receptacle into the low pressure side of said steam header.

In testimony whereof I have hereunto subscribed my name.

JOHN A. WIENER.
